UNITED STATES PATENT OFFICE.

ALBERT F. FIFIELD, OF NEWARK, NEW JERSEY, ASSIGNOR TO THE SINGER MANUFACTURING COMPANY, OF ELIZABETH, NEW JERSEY, A CORPORATION OF NEW JERSEY.

THREAD-CUTTING MECHANISM FOR SEWING MACHINES.

Application filed August 14, 1922. Serial No. 581,606.

To all whom it may concern:

Be it known that I, ALBERT F. FIFIELD, a citizen of the United States, residing at Newark, in the county of Essex and State 5 of New Jersey, have invented certain new and useful Improvements in Thread-Cutting Mechanisms for Sewing Machines, of which the following is a specification, reference being had therein to the accompanying 10 drawings.

This invention relates to thread-cutting mechanism for sewing machines and has for a particular object to improve the mechanism disclosed in my Patent No. 15 1,447,941 of March 6, 1923. In the device of my said copending application it is found that at high speeds there is some danger of the supply limb of the needle-loop being 20 sheared off, together with the work-limb, whereby the thread-end hanging from the needle will be of insufficient length to enable the next sewing operation to be properly started.

Further, in the device of my said application, the bobbin-thread nipper comprises a 25 spring which presses directly against the needle-loop detaining blade and both the bobbin-thread and the supply limb of the needle-loop are caught by the nipper just 30 before the threads are cut. Thus, when the work is removed and the needle-thread end hanging from the needle is thereby pulled out of the nipper, said needle-thread end will sometimes drag the bobbin-thread 35 end out of the nipper and consequently prevent the bobbin-thread end from being held under control when the initial stitch of the next sewing operation is formed.

Further, with my prior device, difficulty 40 is occasionally experienced in providing a beginning needle-thread end uniformly long enough to be gripped by the thread-wiper below the throat-plate at the beginning of a sewing operation, but not so long as to stick 45 out from the finished work.

The present improvement seeks to refine 50 my prior construction and eliminate the sources of the minor difficulties above enumerated to the end that still greater certainty and uniformity of operation will be secured and a uniformly satisfactory product more easily attained.

It is more generally an object of the

present invention to provide a sewing machine having thread-severing mechanism of greater simplicity, durability and dependability than has heretofore been attained.

To the accomplishment of the ends in view, the shank of the ledger-blade of my prior construction has been reversed in position so as to lie within the circular path of action of the needle-loop detaining and severing blade. Also, a pair of cooperative bobbin-thread nipper blades have been mounted in spaced relation with and below the needle-loop detaining and severing blade. These nipper-blades seize and hold the bobbin-thread end independently of the needle-loop detaining blade while the needle-loop passes freely between the nipper-blades and the needle-loop detaining blade.

To insure a beginning thread-end of a minimum uniform length, a ledger-blade has been added to cooperate with a sharpened edge on the thread-wiper to cut off any excess needle-thread projecting beyond the wiper. This ledger-blade is formed with a straight, easily sharpened edge and, to insure certainty of action, an additional blade having a thread-guiding edge inclined to the cutting edge of the ledger-blade is associated with the latter to afford, in effect, a V-notch insuring against escape of the needle-thread end from cutting position between the sharpened edge of the thread-wiper and its cooperative ledger-blade.

In the accompanying drawings, Fig. 1 is a rear side elevation of a sewing machine embodying the invention. Fig. 2 is a bottom plan view of the machine. Fig. 3 is a cross-section through the sewing point longitudinally of the machine bed. Fig. 4 is a bottom plan view of the throat-plate showing the thread-cutting and nipping implements carried thereby. Fig. 5 is a view of the thread-cutting and nipping implement looking in the direction of the arrow 5-5, Fig. 4. Fig. 6 is a bottom plan view of the needle-loop detaining and severing blade and the ledger-blade which cooperates with it. Fig. 7 is a section on the line 7-7, Fig. 4. Fig. 8 is a section on the line 8-8, Fig. 4 and Fig. 9 is a perspective view of the ledger-blade which cooperates with the needle-loop detaining and severing blade to sever the needle and bobbin-threads.

In the preferred embodiment of the invention, as illustrated, 1 represents the machine bed from which rises the standard 2 of the overhanging bracket-arm 3 terminating in the head 4 in which is journaled to reciprocate the needle-bar 5 carrying the eye-pointed needle 6.

The needle 6 cooperates with a loop-taker 7 which is preferably in the form of a rotary hook operating to give the needle-loop a half twist in casting it about the usual bobbin in the thread-case 8, thereby juxtaposing the bobbin-thread and the work-limb of the needle-loop, as explained in my said co-pending application, and enabling the needle and bobbin threads to be cut together at a point close to the work by means of a needle-loop detaining and severing blade having but one cutting edge. The rotary hook 7 is mounted on the shaft 9 which at its rearward end is geared at 10 to the shaft 11 extending vertically within the standard 2 and at its upper end geared at 12 to the main-shaft 13.

The main-shaft 13 is connected as usual to drive the needle-bar 5 and the feed-cam 14 which latter operates through the usual connections to move the work-clamp 15 back and forth over the bed 1 and thus determine the placing of the stitches. As the present machine is intended for sewing on buttons, the work-clamp 15 is of the usual button holding type disclosed, for example, in the patent to C. M. Horton, No. 807,676, of December 19, 1905.

The present machine is equipped with a stop-motion device, constructed substantially in accordance with the disclosure of my said patent and including the stop-motion lever 16 which carries the belt-shifter 17 adjacent the tight and loose pulleys 18, 19, respectively, on the main-shaft 13. The lever 16, as shown in full lines in Fig. 1, is in stopping position. It may be tilted about its pivot 17' to dotted line position to start the machine. At the end of the sewing operation the lever 16 is automatically released and springs to full line or stopping position, whereupon a vertically spring-pressed plunger 20 carried by said lever engages a notch in a stopping cam 21 on the main-shaft 13. The lever 16 is so mounted that it may partake of a sidewise overthrow movement under the action of the stopping cam 21 in coming to rest. This overthrow movement is balanced by the usual buffer spring (not shown) and brings the main-shaft 13 to rest without destructive shock. The present stop-motion device preferably has incorporated therewith a braking device permitting high speed operation, as disclosed in my said patent. The present improvement, however, is not concerned with the mechanism of the braking device and a description of the latter is therefore deemed

unnecessary. In so far as the present improvement is concerned the stop-motion lever 16 is constructed and operated substantially in accordance with the disclosure of said Horton patent.

Mounted below the bed 1 is the usual thread-cutter operating slide-bar 22 which in the present instance is connected at its rear end by means of a link 23 to a lever 24 pivoted at 25 to the bed 1. The lever 25 is connected by a link 26 to an auxiliary slide-bar 27 which at the end of the sewing operation is given the usual two-stage movement; the first stage of such movement being given by the cam-operated lever 28 and the second stage by the overthrow of the stop-motion lever which is transmitted to the slide-bar 27 through the usual bellerank-lever 29. This mechanism for imparting to a thread-cutter operating slide-bar a two-stage movement is old in the art and is disclosed in said Horton patent.

The implements of the present thread-cutting mechanism are mounted on the usual throat-plate 30 from the under side of which projects the pivot-post 31 for the thread-cutter lever-arm 32. The lever-arm 32 is connected to the slide-bar 22 by means of the link 33. The lever-arm 32 has mounted thereon a needle-loop detaining blade 34 similar in shape and function to that disclosed in my said patent. Such blade has at its outer edge an upstanding lip 35 transverse to the plane of the blade 34 and having its inner forward edge 36 sharpened as shown in Figs. 4 and 6. The projection 35 is operatively received in the circular clearance groove 37 in the throat-plate.

The cutting edge 36 of the blade 34 cooperates with the ledger-blade 38 which, together with its shank 39, is disposed within the circle of operation *c*, Fig. 6, of the cutting lip 35. By sharpening the inner forward edge 36 of the lip 35, instead of the outer edge, and by disposing the ledger-blade 38 within, rather than outside of, the circular path of movement of the cutting lip 35 it will be seen upon referring to Fig. 3 that the cutting edge 36 is set inwardly from the outer edge 40 of the loop-detaining blade 34, thereby overcoming the possibility of the supply or lower limb *s* of the needle-loop getting in the path of the cutting blade.

The needle-loop detaining blade 34 has its shank 41 (Fig. 7) offset below the plane of the blade 34 proper. The shank 41 is secured to the carrier arm 32 by means of the screw 42 which also serves to secure a pair of bobbin-thread nipper-blades 43, 44 in a position spaced below the needle-loop detaining blade 34. The blade 43 is preferably made relatively stiff and the blade 44 springy. The ends of these blades are oppositely curved to form a mouth 45, Fig. 4, which catches the bobbin-thread *b*, and

directs it between the nipper-blades 43, 44, Fig. 3, during the first stage of movement of the carrier-lever 32.

When the machine is sewing, the carrier-lever 32 and blades 34, 43 and 44 occupy a retracted position indicated in dotted lines in Fig. 4. As the sewing operation is nearing completion the usual thread-cutter operating cam-groove 46 in the feed-wheel 14 5 acting through the lever 28, imparts to the slide-rod 22 its first stage of movement which causes the needle-loop detaining blade 34 to be projected into the last needle-loop as the latter is being passed around the bobbin by the rotary hook 7. After the 10 take-up has acted, the last needle-loop is thus detained below the work in a spread condition by the blade 34. The inner edge of the blade 34 also catches the bobbin-thread 20 *b* and directs said thread into the mouth 45 of the nipper 43, 44, at the same time serving to pull off enough bobbin-thread to insure the interlocking of the latter with the needle-thread when the initial 25 stitch of the next sewing operation is formed. The supply limb of the needle-loop passes freely between the loop-detaining blade 34 and the upper-blades 43, 44, while the work-limb *w* of the needle-loop and the bobbin-thread *b* extend in juxtaposed relation 30 above the blade 34 directly in the path of the cutting lip 35, and between the latter and the ledger-blade 38, as shown in Fig. 3. The overthrow motion of the stop-lever 16, 35 in bringing the main-shaft 15 to rest, operates in the usual manner to impart the second stage of movement to the slide-bar 22 which transmits to the blade 34 a cutting impulse carrying the lip 35 into shearing engagement with the ledger-blade 38 and thereby severing the bobbin-thread *b* and the work-limb *w* of the needle-loop close to the work.

Mounted on the carrier-lever 32 is a 40 thread-wiper or gripper 47 of usual hooked form which is adapted to nip the beginning end of the needle-thread against the under side of the throat-plate 30. In the present instance the edge 48 of the thread-gripper 45 is sharpened for cooperation with the sharpened straight edge 49 of a ledger-blade 50 secured to the throat-plate 30, to cut off any 50 excess of needle-thread sticking out beyond the gripper and thus insure a needle-thread end of a uniform minimum length, i. e., no longer than is essential to the secure holding of such thread-end by the gripper 47 during the formation of the initial stitches. A second blade 51 having a thread-guiding 55 point 52 underlying the cutting edge 49 and directed at an angle to the latter is provided for catching the needle-thread end and directing it to the cutting edge 49 of the ledger-blade 50. The finger 52 together with the 60 cutting edge 49 forms a V-notch insuring

against escape of the thread. This construction has an advantage over a single ledger-blade formed with a V-notch in that the straight cutting edge 49 may be separated from the finger 52 and easily sharpened on an ordinary grinding wheel.

Having thus set forth the nature of the invention, what I claim herein is:

1. In a sewing machine, the combination 75 with a throat-plate, of a needle-loop detaining blade mounted below the throat-plate to swing about an axis transverse to the plane of the throat-plate, said blade having a blunt outer curved edge and a portion extending toward said throat-plate, said portion having a cutting edge disposed inwardly from said outer edge.

2. In a sewing machine, the combination 80 with a throat-plate, of a needle-loop detaining blade mounted below the throat-plate to swing about an axis transverse to the plane of the throat-plate, said blade having a blunt outer curved edge and a cutting edge disposed inwardly from said outer edge, and a ledger-blade mounted inwardly from said cutting edge and cooperating with the latter to sever the thread.

3. In a sewing machine, the combination 85 with a throat-plate, of a needle-loop detaining blade mounted below said throat-plate on an axis transverse to the plane of the throat plate, and a bobbin-thread nipper mounted in spaced relation with and below said needle-loop detaining blade.

4. In a sewing machine, the combination 100 with a throat-plate, of a carrier mounted on the under side of said throat-plate, a needle-loop detaining blade mounted on said carrier, and a bobbin-thread nipping device also mounted on said carrier in spaced 105 relation with said needle-loop detaining blade so as not to nip the thread of the needle-loop.

5. A thread-cutting mechanism for sewing machines comprising, a flattened needle-loop detaining blade pivoted transversely of the planes of its faces and having a curved outer edge and a cutting lip disposed at said outer edge and at an angle to the faces of said blade, said lip having a cutting edge disposed inwardly from the outer edge of said blade.

6. In a sewing machine, the combination 110 with a thread-wiper in the form of a hook adapted to grip the beginning end of the needle-thread below the work and having adjacent its hooked extremity a rearwardly directed cutting edge, of a ledger-blade having a straight sharpened edge, and a second 115 blade detachable from said ledger-blade and formed with a thread-guiding edge disposed at an angle to said ledger-blade and forming therewith a V-notch, substantially as and for the purposes specified.

7. The combination with stitch-forming 120

mechanism including a reciprocating needle, a bobbin and a rotary hook adapted to give the needle-loop a half twist in casting it about the bobbin and juxtapose the bobbin-thread and the work-limb of the needle-loop, of a needle-loop detaining and severing blade having a bobbin-thread pull-off edge, a pair of bobbin-thread nipper-blades spaced from said blade and adapted to seize only

the bobbin-thread while permitting the 10 needle-loop to pass freely between the needle-loop detaining blade and the nipper-blades, and means for severing the juxtaposed threads.

In testimony whereof, I have signed my 15 name to this specification.

ALBERT F. FIFIELD.
